GOBLET OR SIMILAR ARTICLE

Carl J. Uhrmann, Bellaire, Ohio, assignor to Imperial Glass Corporation, Bellaire, Ohio, a corporation of Ohio

Application January 7, 1949, Serial No. 118

Term of patent 14 years

(Cl. D36—8)

To all whom it may concern:

Be it known that I, Carl J. Uhrmann, a citizen of the United States, residing at Bellaire, county of Belmont, and State of Ohio, have invented a new, original, and ornamental Design for a Goblet or Similar Article, of which the following is a specification, reference being had to the accompanying drawing, forming a part thereof.

Figure 1 is a side elevational view of a goblet or similar article showing my new design, and

Figure 2 is a sectional view taken on line 2—2 of Fig. 1.

The dominant features of the design reside in the parts drawn in full lines as shown.

I claim:

The ornamental design for a goblet or similar article, substantially as shown and described.

CARL J. UHRMANN.
